UNITED STATES PATENT OFFICE.

WILLIS H. CARRIER, OF ESSEX FELLS, NEW JERSEY, ASSIGNOR TO CARRIER ENGINEERING CORPORATION, OF NEWARK, NEW JERSEY.

METHOD OF AND APPARATUS FOR DRYING AND CONDITIONING MATERIALS.

Application filed October 14, 1921. Serial No. 507,670.

To all whom it may concern:

Be it known that I, WILLIS H. CARRIER, a citizen of the United States, residing at Essex Fells, in the county of Essex and State of New Jersey, have invented a new and useful Improvement in Methods of and Apparatus for Drying and Conditioning Materials, of which the following is a specification.

10 This invention relates to methods of and apparatus for drying materials. In the drying of materials, it is desirable in order to attain the best results, to use different rates or schedules of drying effects for the different materials, depending upon their different characteristics or the final results required. It is also an advantage to be able to dry a material in accordance with one or another definite drying schedule so as to obtain different desired results. With some materials the final stages of the drying process can be carried on more rapidly than with other materials. For instance, in the case of macaroni, the best results are secured by a 15 relatively slow drying at the end while many other materials permit of a more rapid, final drying.

One of the primary objects of this invention is to produce a definite predetermined schedule of the rate of drying, the rate of drying being more rapid at the beginning and decreasing slowly or gradually as the material dries. A conspicuous novel feature of the system is that the drying capacity is definitely predetermined and fixed by introducing a relatively small but constant amount of air having a constant temperature and a definite degree of dryness, that is a definite moisture content or a 20 definite wet bulb temperature with respect to the dry bulb temperature. An important advantage of this process is that the schedule can be varied to suit particular individual requirements of materials by simply reducing the air quantity and raising its temperature, or increasing the air quantity and reducing its temperature, giving the same total rate of drying with the same wet bulb temperature. In the first case, the rate 25 of drying will be more evenly sustained, that is it will be more nearly uniform throughout the drying process until the material is completely dried. In the second case, the rate of drying will fall off more rapidly as the drying progresses and may

become exceedingly slow at the last part of the drying, which is a necessary requirement in drying certain products.

By this system the amount of drying can be definitely measured and controlled from a 30 source independent of conditions in the room itself. The difference between controlling this way and controlling in the room is that in the room control one gets a constant condition of temperature and relative 35 humidity while by this system one gets a progressively increasing temperature and correspondingly progressive, decreasing relative humidity. If this same result were to be obtained by controlling the conditions 40 in the room, it would be necessary either to make frequent adjustments of the control instruments by hand or have an automatically adjusting or changing instrument located in the room to give the required 45 schedule. As disclosed in this case, the control is effected by independently regulating the wet bulb and dry bulb temperatures of the air supplied, but it could also be accomplished by other means which would fix the 50 moisture content of the entering air, as for instance, by controlling the dew point of the entering air or controlling the relative 55 humidity of the entering air by means of a hygrostat.

Other objects of the invention are to accomplish such results by a method and apparatus in which a relatively large volume of air is circulated for the treatment of the material, but in which it is only necessary to condition a relatively much smaller volume of air so that large quantities of material can be properly dried with definite results, by means of a comparatively small and inexpensive apparatus handling only a 60 small quantity of air; also to improve and simplify drying systems in the other respects hereinafter described and set forth in the claims.

It is known that the absorption of one grain of moisture per cubic foot of air lowers the dry bulb temperature of the air approximately $8\frac{1}{2}$ degrees. Therefore, the number of grains of moisture evaporated from the material by each cubic foot of air 65 will be equal to the drop in temperature between the air entering and leaving the material divided by $8\frac{1}{2}$. In the method and apparatus of this application, this principle is employed and the rate of drying of the 70

material is definitely predetermined as required by fixing or determining the volume and the moisture content of the air supplied to the drying chamber so as to give the required drop in the temperature between the air entering and leaving the material. According to this method, the drying is effected and the rate of drying definitely controlled as required, depending upon the characteristics of the material being dried, by supplying to the drying chamber a relatively small volume of air which is caused to mix with a relatively much larger volume of air in the drying chamber, circulating the mixed air through the material and regulating the volume and condition of this relatively small volume of air supplied to the drying chamber so as to maintain a predetermined wet bulb temperature in the drying chamber and give a predetermined, definite drop in temperature between the air supplied to the drying chamber and the air leaving the material. The required temperature and humidity of the air supplied to the chamber can be obtained by various means but preferably by mixing outside air and return air from the chamber and adding moisture and heat as may be necessary to give such required temperature and humidity to the air supplied.

My improved method of drying is explained in detail in connection with the description of the operation of the apparatus for carrying out the method.

35 In the accompanying drawings, apparatus of three slightly different arrangements are illustrated for carrying out the method.

Fig. 1 is a partly diagrammatic longitudinal sectional elevation of an apparatus embodying the invention and adapted for carrying out my improved method.

40 Fig. 2 is a sectional plan view thereof, on line 2-2, Fig. 1.

Fig. 3 is a sectional plan view thereof, on 45 a reduced scale, on line 3-3, Fig. 1.

Fig. 4 is a view similar to Fig. 1 of an apparatus of slightly modified arrangement.

Fig. 5 is a sectional plan view thereof on line 5-5, Fig. 4.

50 Fig. 6 is a view similar to Fig. 1 of still another arrangement of apparatus embodying the invention.

Fig. 7 is a sectional plan view thereof on line 7-7, Fig. 6.

55 Referring first to Figs. 1 to 3, A represents a drying chamber in which the material B is preferably arranged on trucks, racks, trays or otherwise, as may be most suitable, depending upon the nature of the material, so as to leave unobstructed spaces in the chamber at three adjoining sides of the material, that is, for instance, at opposite ends of and above the material, and provide flow passages for the air through the material, preferably arranged so that the air

can circulate horizontally through the material from one end of the chamber or the other, as indicated by the arrows.

10 represents a supply duct for delivering air, conditioned as to temperature and humidity, to the drying chamber. In the arrangement shown in Figs. 1 to 3, this supply duct 10 is provided with a discharge head 11 equipped with a plurality of nozzles 11^a and extending horizontally across the chamber in a space 13 between one end of the material and a plurality of air circulating fans 14 arranged in openings in a partition 15 extending across the drying chamber. These fans, the number of which depends upon the width of the drying chamber, and which may be driven by any suitable drive mechanism, draw the air in the chamber through the material and force it up into the near end of the unobstructed space above the material and also draw in air through the supply duct 10, causing it to mix with the larger volume of circulating air in the chamber and causing the mixed air to circulate in the chamber and repeatedly pass through the material, as indicated by the arrows. Preferably a false ceiling 15^a extends from the partition 15 lengthwise in the drying chamber above the material, forming a space through which the air discharged by the fans 14 flows to the opposite end of the material.

16 represents a return air duct leading from the end of the chamber at which the fans are located to the air supply duct 10, and the latter is provided with an open, outer end 17 for the admission of outside or fresh air.

The ducts 10 and 16 are controlled by fresh and return air dampers 18 and 19 of any suitable sort connected by suitable mechanism 20 whereby the opening of one damper will cause the closing of the other damper, thus enabling any desired proportion of outside or fresh air and return air from the chamber to be supplied to the chamber.

21 represents a steam radiator or heater for heating the air supplied to the drying chamber and 22 represents means, preferably consisting of one or more steam discharge nozzles for increasing the humidity of the air supplied to the drying chamber.

The dry bulb temperature of the air supplied to the drying chamber is controlled preferably by a dry bulb thermostat 23, which is arranged so as to be influenced by the temperature of the air supplied to the drying chamber and controls the heater 21 through any suitable or usual instrumentalities, such as a diaphragm valve 24 in the steam supply pipe 25 for the heater and

actuated by compressed air supplied by a pipe 26 under the control of the thermostat 23. The wet bulb temperature of the air supplied to the drying chamber is controlled

115 preferably by a wet bulb thermostat 27 in the steam supply pipe 25 for the heater and

actuated by compressed air supplied by a pipe 26 under the control of the thermostat 23. The wet bulb temperature of the air supplied to the drying chamber is controlled

120 preferably by a wet bulb thermostat 27 in the steam supply pipe 25 for the heater and

actuated by compressed air supplied by a pipe 26 under the control of the thermostat 23. The wet bulb temperature of the air supplied to the drying chamber is controlled

125 preferably by a wet bulb thermostat 27 in the steam supply pipe 25 for the heater and

actuated by compressed air supplied by a pipe 26 under the control of the thermostat 23. The wet bulb temperature of the air supplied to the drying chamber is controlled

130 preferably by a wet bulb thermostat 27 in the steam supply pipe 25 for the heater and

which is located so as to be influenced by the wet bulb temperature of the air supplied to the drying chamber, and controls the steam nozzle 22 and the fresh and return air dampers 18 and 19 through any suitable or usual instrumentalities, such as a diaphragm valve 28 in the steam supply pipe for the nozzle 22, and a damper actuating motor 29, the diaphragm valve 28 and motor 29 being actuated by compressed air supplied by a pipe 30 under the control of the wet bulb thermostat 27. The dry bulb and wet bulb thermostats 23 and 27 are adapted to regulate respectively the dry and wet bulb temperatures of the air supplied by the duct 10 to the drying chamber so that the air will be delivered to the chamber with a definite dry bulb temperature of, for example 152° F. and a definite wet bulb temperature of for example 100° F. The dry bulb thermostat is adapted to regulate the supply of steam to the heater 21 so as to maintain this dry bulb temperature and the wet bulb thermostat 27 is adapted to regulate the discharge of steam from the nozzle 22 and change the position of the fresh air and return air dampers 18 and 19 so as to maintain this predetermined wet bulb temperature.

31 represents a duct for the relief of air from the drying chamber, the duct preferably leading from the space 13 in the chamber between the air circulating fans 14 and the adjacent end of the material B.

In the slightly different arrangement of the apparatus shown in Figs. 4 and 5, the disposition of the material in the drying chamber and the means for regulating the dry bulb and wet bulb temperatures of the air supplied to the drying chamber are the same as explained above, but the arrangement of the air supply means is different. In this Fig. 4-5 arrangement, the conditioned air is supplied to the chamber by a fan 35 located in the air supply duct 10 and the discharge head 36 of the supply duct extends across the drying chamber in the lower portion of the space 37 between the adjacent end of the drying chamber and the partition in which the circulating fans 14 are located. In other words, the air supplied by the supply duct 10 is delivered by the fan 35 into the drying chamber at the pressure side of the circulating fans and is mixed with the larger volume of the air in the drying chamber and circulated through the drying chamber and material by the fans 14. Otherwise, the control and operation of the system is the same as above described.

In the apparatus as shown in Figs. 6 and 7 the air supply duct 10 leads to a fan 40 which is disposed in the drying chamber in the space between one end of the chamber and the adjacent end of the material and this fan is provided with a discharge duct 41 con-

ected with a discharge head 42 which extends across the drying chamber in the upper portion thereof and is provided with a series of nozzles 43 disposed so as to discharge the air into the unobstructed space 70 above the material toward the far end of the chamber. The fan 40 is adapted to draw in the air from the supply duct and also to draw the larger volume of air in the drying chamber through the material and mix the air from the supply duct 10 with the other air in the chamber and discharge the mixed air into the space in the chamber above the material. The discharge of the air at a relatively high velocity from the nozzles 43, and the suction of the fan 40 intimately mixes the conditioned incoming air with the other air in the drying chamber and induces a circulation of the whole volume of air in the chamber through the material. In this arrangement, as in the others described, the control of the wet and dry bulb temperatures of the air supplied to the drying chamber is the same as above described and the operation of the system and maintenance of the conditions in the drying chamber are the same.

In each of the three different apparatus illustrated a relatively small volume of conditioned air is supplied to the drying chamber and is intimately mixed with the other air in the drying chamber and the entire volume of this mixed air, which is many times greater than that of the conditioned air supplied, is circulated so as to flow through or over and dry the material in the chamber. The relief duct permits the escape from the chamber of an amount of air equal to the amount supplied by the duct 10, so that a substantially constant volume of air acts on the material at all times.

In drying material by the apparatus and in accordance with the method of this invention, the ratio of the volume of conditioned air entering the drying chamber to the entire volume of air circulated through the material is approximately inversely proportional to the ratio of the drop in temperature of the respective volumes of air. For example, if the air is supplied by the duct 10 with a dry bulb temperature of 152° and leaves the chamber at 106°, and the entire circulating body of air in the chamber enters and leaves the material at temperatures of 108° and 106° respectively, then the volume of conditioned air supplied to the chamber should be approximately 1/22 of the entire volume of air circulated in the drying chamber. If the heat transmission through the walls of the drying chamber is negligible, which is readily possible in a properly constructed drying chamber, the wet bulb temperature of the air circulating in and leaving the drying chamber will remain the same as that of the air supplied to the chamber in

accordance with the psychometrical principle governing the evaporation of moisture. The dry bulb temperature of the drying chamber and material will increase, however, 5 and produce a gradually increasing wet bulb depression and decreasing relative humidity in the drying chamber as the drying proceeds and the moisture in the material lessens. The rate of drying is determined by 10 the difference in temperature of the conditioned air entering and leaving the drying chamber, and any desired constant or decreasing rate of drying can be obtained by fixing the volume and temperature of the 15 conditioned air supplied to the drying chamber to suit the drying conditions required. The volume of the air supplied can be regulated by any suitable means such as an ordinary hand actuated damper in the air supply duct 10. When the appropriate volume and temperature for the entering air have been determined, the volume and temperature thereof remain constant throughout the drying process or a desired period thereof. 20 Since the drying tendency is proportional to the wet bulb depression for a given quantity of moisture in the material, a more rapid drying at the end of the drying period can be secured by supplying a comparatively 25 small volume of air at a high temperature, while a larger volume of air with a lower temperature will give a less rapid drying at the finish.

I claim as my invention:

35 1. The hereindescribed method of drying material which consists in circulating a body of air through the material in a drying chamber, supplying to and mixing with said circulating body of air a relatively much 40 smaller volume of air, maintaining a predetermined wet bulb temperature of said smaller volume of supplied air previous to its supply to the chamber, and causing said smaller volume of supplied air to enter the 45 drying chamber with a predetermined dry bulb temperature higher than the temperature of the circulating mixed air entering and leaving the material, whereby a predetermined weight of moisture is evaporated 50 per unit quantity of the smaller volume of air supplied.

2. The hereindescribed method of drying material which consists in circulating a body of air through the material in a drying 55 chamber, supplying to and mixing with said circulating body of air a relatively much smaller substantially constant volume of air, maintaining a constant wet bulb temperature of said smaller volume of supplied air 60 previous to its supply to the chamber, and regulating the dry bulb temperature of said smaller volume of supplied air so that said air enters the drying chamber with a substantially constant dry bulb temperature 65 higher than the temperature of the circulat-

ing mixed air entering and leaving the material, whereby a predetermined weight of moisture is evaporated per unit quantity of the smaller volume of air supplied.

3. The hereindescribed method of drying 70 material which consists in circulating a body of air through the material in a drying chamber, supplying to and mixing with said circulating body of air a relatively much smaller volume of air, maintaining a predetermined wet bulb temperature of said smaller volume of supplied air previous to its supply to the chamber, and regulating the dry bulb temperature of said smaller volume of air so that said supplied air enters the 75 drying chamber with a dry bulb temperature higher than the temperature of the circulating air entering and leaving the material and such as to maintain a predetermined drop in temperature between the air entering and leaving the material.

4. The hereindescribed method of drying 80 material which consists in circulating a body of air through the material in a drying chamber, supplying to and mixing with said circulating body of air a relatively much smaller volume of air, maintaining a predetermined wet bulb temperature of said smaller volume of supplied air previous to its supply to the chamber, and predetermining the volume and temperature of said smaller volume of supplied air so that the 85 ratio of the volume of conditioned air entering the drying chamber to the entire volume of air circulating through the material will 90 be approximately inversely proportional to the ratio of the drop in temperature of the respective volumes of air.

5. The hereindescribed method of drying 95 material which consists in circulating a body of air through the material in a drying chamber, supplying to and mixing with said circulating body of air a relatively much smaller volume of air, maintaining a predetermined wet bulb temperature of said smaller volume of supplied air previous to its supply to the chamber by mixing fresh air and return air from the drying chamber and regulating its humidity under the control of the wet bulb temperature of said air supplied to the drying chamber, and regulating the dry bulb temperature of said smaller volume of supplied air, so that said supplied air enters the drying chamber with a predetermined dry bulb temperature 105 higher than the temperature of the circulating mixed air entering and leaving the material, whereby a predetermined weight of moisture is evaporated per unit quantity of the smaller volume of air supplied.

6. In an apparatus for drying material, the combination of a drying chamber in which the material is located, means for circulating the air in said chamber through the material, means for supply to and mixing 110

- with said circulating body of air a relatively much smaller volume of conditioned air, means for the relief of air from the drying chamber, means for regulating the humidity 5 of said smaller volume of supplied air previous to its supply to the chamber to maintain a predetermined wet bulb temperature thereof, and means for regulating the temperature of said smaller volume of supplied 10 air previous to its supply to the chamber and maintaining the same at a dry bulb temperature higher than the temperature of the circulating mixed air entering and leaving the material.
- 15 7. In an apparatus for drying material, the combination of a drying chamber in which the material is located, means for circulating the air in said chamber through the material, means for supplying to and mixing 20 with said circulating body of air a relatively much smaller volume of conditioned air, means for the relief of air from the drying chamber, means for regulating the humidity of said smaller volume of supplied 25 air previous to its supply to the chamber, a heater for heating said supplied air previous to its supply to the chamber, a wet bulb thermostat influenced by said supplied air and controlling said humidity regulating means, and a dry bulb thermostat influenced 30 by the temperature of said supplied air and regulating said heater.
8. In an apparatus for drying material, the combination of a drying chamber in 35 which the material is located, means for circulating the air in said chamber through the material, a duct for supplying to and mixing with said circulating body of air a relatively much smaller volume of conditioned 40 air, said duct having a fresh air inlet, means for the relief of air from said drying chamber, a return air duct leading from said drying chamber to said supply duct, dampers controlling said fresh air inlet and return 45 air duct, moisture supply means in said supply duct, a heater in said supply duct, a wet bulb thermostat in said supply duct controlling said dampers and said moisture supply means, and a dry bulb thermostat in said 50 supply duct controlling said heater, whereby
- said supplied air is maintained at a predetermined wet bulb temperature and at a dry bulb temperature higher than the temperature of the air entering and leaving the material. 55
9. In an apparatus for drying material, the combination of a drying chamber in which the material is located, a fan which circulates the air in said chamber for drying the material, an air supply duct arranged to deliver a relatively much smaller volume of conditioned air into the chamber to mix and circulate with the other air in the chamber, said duct having a fresh air inlet, means for the relief of air from the drying chamber, a return air duct leading from the drying chamber to said supply duct, means for regulating the wet bulb temperature of the air supplied to the drying chamber previous to its admission to the chamber including means for controlling the proportions of fresh air and return air supplied to the chamber, and means for regulating the dry bulb temperature of the air supplied to the drying chamber previous to its admission to the chamber, whereby said supplied air is maintained at a predetermined wet bulb temperature and at a dry bulb temperature higher than the temperature of the air entering and leaving the material. 60 65 70 75
10. The herein-described method of drying material which consists in circulating a body of air through the material in a drying chamber, supplying to and mixing with said circulating body of air a relatively much 80 smaller volume of air, regulating the moisture content of said smaller volume of supplied air previous to its admission to the chamber so that said supplied air enters the chamber with a predetermined moisture content, and regulating the dry bulb temperature of said smaller volume of supplied air so that the dry bulb temperature of said supplied air entering the chamber is higher than the temperature of the circulating air 85 entering and leaving the material and such as to maintain a predetermined drop in temperature between the air entering and leaving the material. 90 95

WILLIS H. CARRIER.
